Primary Examiner — Rosemary K Tarcza*(74) Attorney, Agent, or Firm* — Klauber & Jackson LLC(57) **CLAIM**

The ornamental design for a charging station with tablets, as shown and described.

DESCRIPTION

FIG. 1 is a perspective view of the front, top and left side of a charging station with tablets showing our new design;

FIG. 2 is a top view thereof;

FIG. 3 is a front elevation view thereof;

FIG. 4 is a rear view thereof;

FIG. 5 is a left side view thereof;

FIG. 6 is a right side view thereof;

FIG. 7 is a bottom view thereof;

FIG. 8 is a perspective view similar to FIG. 1, depicting the keyboard on the upper forward surface thereof in broken lines;

FIG. 9 is front elevation view similar to FIG. 2, depicting the keyboard on the upper forward surface thereof in broken lines and,

FIG. 10 is a top view similar to FIG. 3, depicting the keyboard on the upper forward surface thereof in broken lines.

The broken lines shown in the drawings are included for the purpose of illustrating environmental structure and form no part of the claimed design.

1 Claim, 5 Drawing Sheets(56)
